COLOSTOMY CONTROL DEVICE

Carl F. Surface, Des Moines, Iowa

Application December 6, 1947, Serial No. 790,125

3 Claims. (Cl. 128—1)

1

This invention relates generally to medical instruments and in particular to a colostomy control device for periodically opening and closing the anus of a colostomy patient.

Colostomy patients are generally hesitant to engage in regular work and social activities because of the fear of embarrassment. Although colostomy control devices now commercially available are generally satisfactory, some of them are objectionable because of their bulk which makes them easily discernible in use, their inability to properly block the anus, their requiring parts which are inconvenient to carry about when not in use for inserting the colostomy control device within the anus of the colostomy patient, and their pressing on certain parts of the abdomen of the colostomy patient so as to make their use uncomfortable.

It is an object of this invention, therefore, to provide an improved colostomy control device.

A further object of this invention is to provide a colostomy control which permits a patient to engage in regular activities without fear of embarrassment.

Yet another object of this invention is to provide a colostomy control device which is of a compact construction, easily used in the opening and closing of the anus of the colostomy patient, adapted to be worn without discernment and capable of effectively blocking the passage of fecal material through the anus.

A feature of this invention is found in the provision of a colostomy control device in which a resilient tubular member is formed at one end with a hollow, extendible and contractible head member of a disc shape adapted to be extended axially of the tubular member. The other end of the tubular member projects through and is attached to a disc or pad member having an annular portion for contacting the abdominal wall of the colostomy patient about the outer end of the anus formed in such wall. The tubular member, between the disc member and the head member, is of a length substantially equal to the thickness of the abdominal wall, whereby on extension of the head member the tubular member is insertable within the anus to position the head member within the intestine of the patient. The head member, on being contracted, is adapted to contact the abdominal wall about the inner end of the anus so as to effectively stop the passage of fecal discharge from the intestine through the anus.

Further objects, features and advantages of this invention will become apparent from the

2

following description when taken in connection with the accompanying drawings, in which:

Fig. 1 is a side elevational view of the colostomy control device of this invention, with parts shown in section, shewing the device in its assembled or used position within the anus of a colostomy patient;

Fig. 2 is a side elevational view, illustrated similarly to Fig. 1, showing the manner of inserting the colostomy control device within the anus of a colostomy patient;

Fig. 3 is a longitudinal sectional view of the control device; and

Fig. 4 is an exploded perspective view of the control device.

With reference to the drawings, the colostomy device of this invention, indicated generally at 10, is shown in Fig. 1 in its position within an anus 11 of a colostomy patient for blocking or stopping the passage of fecal material from the alimentary canal or intestine 12 through the anus. The anus 11 is illustrated as being formed in the abdominal wall, designated generally as 13, and comprising an epithelium layer 14 and a peritoneal lining 16, so that the thickness of the abdominal wall is equal to the combined thicknesses of the epithelium layer and the peritoneal lining.

In colostomy operations the discharge end 17 of the intestine 12 is usually secured to the inner end 18 of the anus 11 so that a portion 19 of the intestine extends in a substantially parallel relation along the inner surface of the peritoneal lining 16 and about the inner end 18 of the anus. The intestine portion 19 thus constitutes a substantially annular shoulder within the intestine at its junction with the abdominal wall.

The colostomy device 10 includes a tubular member 21 of a rubber or like resilient composition (Figs. 3 and 4) integrally formed at one end with a hollow, extendible and contractible head member 22, which is of a disc shape. The head member 22 is concentrically arranged relative to the tubular member 21 so as to be capable of extension in substantial axial alignment with the tubular member. It is contemplated that the wall of the tubular member 21 be of a somewhat greater thickness than the wall of the hollow head member 22 to provide some rigidity in the tubular member, and to facilitate the expansion and contraction of the head member 22.

The outer or opposite end 23 of the tubular member 21 is integrally formed with a pair of axially spaced circumferential beads 24 and 26. The end 23 of the tubular member 21 is detach-

ably connected with a disc or pad member 27 of an aluminum composition, and of a substantially saucer shape. The central section 28 of the disc is depressed and formed with a center opening 29. From the depressed section 28, the disc is curved outwardly and then inwardly so that its peripheral section 31 is adapted to contact the outer surface of the epithelium layer 14 at a spaced position about the outer end 32 of the anus 11.

The disc opening 29 is of a diameter substantially equal to the diameter of the tubular member 21, so that on insertion of the circumferential bead 24 through the opening 29, the wall of the opening is received within the recess 33 between the beads 24 and 26 so as to be in frictional releasable engagement with the inner adjacent sides of the beads 24 and 26 and with the bottom of the recess 33. Stated otherwise, the beads 24 and 26 are arranged at opposite sides of the disc member 27 in what might be termed a grommet connection with the disc.

In the use of the colostomy device the head member 22 is extended by the provision of a pin member 34 of a wood or other suitable material (Figs. 2 and 4) of a length greater than the tubular member 21 and adapted to be inserted within the tube through its open outer end 23. By pressing the pin 34 inwardly of the tube 21 and against the wall section 36 of the head member 22, the head member is axially extended to its position illustrated in Fig. 2, whereby the tubular member 21 is readily insertable within the anus 11. In the insertion of the tubular member 21 within the anus, the rim portion 37 of the head member 22 is readily collapsed by the anus wall on its passage through the anus.

It is contemplated that the length of the tubular member 21 between the circumferential bead 26 and the head member 22, be substantially equal to the thickness of the abdominal wall 13. As a result, on insertion of the tubular member 21 within the anus 11, to a position defined by the engagement of the disc 27 with the outer surface of the abdominal wall 13, the head member 22 is positioned within the intestine 12 inwardly of the shoulder portion 19. On removal of the pin 34 from within the tubular member 21, the head member 22 is permitted to contract to its position illustrated in Fig. 1, so that its peripheral section 37 moves into contact engagement with the intestine shoulder 19. The inner end 18 of the anus 11 is thus completely blocked so as to prevent the passage of fecal material from the intestine 12 therethrough.

From a consideration of Fig. 1, it will be apparent that any pressure built up by the fecal material within the intestine 12, will act to hold the shoulder 19 and peripheral or rim section 37 in closer contact engagement. Further, the resiliency of the head member 22 prevents the application of any pressure, on contraction of the head member 22, from being applied on the intestine 12 or against the abdominal wall 13 so as to effect any uncomfortable feeling to the colostomy patient.

Any liquid seepage from about the head member 22 and through the anus 11 about the tubular member 21 is prevented from passing outwardly from under the disc 27 by merely arranging a suitable pad material (not shown) within the space 38 formed between the outer surface of the abdominal wall 13 and the outward convexly curved section 39 of the disc member 27. It will be understood, of course, that a flexible belt or

girdle (not shown) is worn by the colostomy patient so as to extend over the disc 27.

In the removal of the colostomy device the pin 34 is re-inserted within the tubular member 21 and manipulated to again extend the head member 22. With the head member 22 in its extended position, as shown in Fig. 2, the device is moved outwardly from the anus 11.

From a consideration of the above description, 10 it is seen that the invention provides a colostomy control device which is of a compact and simple construction, and readily and conveniently manipulated for the purpose of periodically opening and closing the anus 11. When the device 15 is in use, the colostomy patient need only carry about with him the pin 34 which can be readily carried within a pocket or a purse. It is apparent, of course, that a pencil or the like would be used in place of the pin 34 in emergency cases.

20 The abdominal wall 13 varies in thickness for different persons. The tubular member 21, therefore, will thus vary in length according to the thickness of the abdominal wall. It will be appreciated also that the tubular member 21 will 25 deteriorate as a result of the action thereon of the fecal material discharged from the intestine 12. By virtue of the detachable connection of the tubular member 21 with the disc member 27 it is only necessary, under such conditions, to 30 replace the tubular member 21.

Although the invention has been described and illustrated with respect to a preferred embodiment thereof, it is to be understood that it is not to be so limited since changes can be made 35 therein which are within the full intended scope of the invention as defined by the appended claims.

I claim:

1. A device for periodically opening and closing the anus of a colostomy patient, comprising a disc member having a depressed center portion formed with a central opening and an inwardly curved peripheral portion adapted to contact the abdominal wall of the patient about the outer end of said anus, a tubular member insertable within said anus and formed at one end with a resilient hollow extendible and contractible head member of a disc shape, with said head member being open to the space within said tubular member, and means for attaching the other end of said tubular member with said disc member at the central opening therein, said head member, on extension thereof, being insertable through said anus and into the intestine of the patient, and said tubular member being of a length between said disc member and head member substantially equal to the thickness of the abdominal wall whereby said head member, on contraction thereof, is engageable with the abdominal wall about the inner end of said anus so as to block the discharge of fecal material from the intestine through said anus.
2. A device for periodically opening and closing the anus of a colostomy patient, comprising a resilient tubular member integrally formed at one end with a hollow disc shape head member open to said tubular member and capable of being extended into substantial axial alignment with said tubular member, a pair of axially spaced circumferential beads at the other end of said tubular member, with said tubular member, between the inner one of said beads and said head member, having a length substantially equal to the thickness of the abdominal wall of the patient, and a disc member formed with a central

opening therein adapted to receive the other end of the tubular member such that said pair of ribs are arranged at opposite sides of said disc and in releasable frictional engagement with the surface portions thereof surrounding said opening, with the peripheral portion of said disc being adapted to contact the abdominal wall about the outer end of said anus, said tubular member, on extension of said head member, being insertable within said anus to position the head member within the intestine of the patient, and said head member, on contraction thereof, being adapted to engage the abdominal wall about the inner end of said anus whereby to block the passage of fecal material from said intestine through said anus.

3. A device for periodically opening and closing the anus of a colostomy patient, comprising a disc member having a central opening therein and formed with an annular portion adapted to contact the abdominal wall of the patient about the outer end of said anus, a tubular member having an extensible and contractible hollow head member of a disc shape at one end adapted to be extended into substantial axial alignment with said tubular member, means for connecting

the other end of said tubular member with said disc member at the central opening therein, and a pin member insertable within said tubular member for extending said head member, with said tubular member having a length between said head member and disc member substantially equal to the thickness of said abdominal wall, said head member, on extension thereof, being insertable within said anus to a position within the intestine of the patient, such that on contraction, thereof, by withdrawal of said pin member, said head member is engageable with the abdominal wall about the inner end of said anus so as to block the passage of fecal material from said intestine through said anus.
